UNITED STATES PATENT OFFICE.

ROBERT ELMER BAKER, OF BRONXVILLE, EARDLEY HARRY FORD, OF BROOKLYN, AND IRWIN ELLIOTT, OF NEW YORK, N. Y., ASSIGNEES, BY MESNE ASSIGNMENTS, TO JOSEPH BAKER SONS & PERKINS COMPANY, INC., OF WHITE PLAINS, NEW YORK, A CORPORATION OF NEW YORK.

PUMP-OPERATING MECHANISM FOR WAFER-BAKING MACHINES.

1,407,457.

Specification of Letters Patent. Patented Feb. 21, 1922.

Application filed December 2, 1918. Serial No. 264,977.

To all whom it may concern:

Be it known that we, ROBERT ELMER BAKER, a subject of the King of Great Britain, and resident of Bronxville, in the 5 county of Westchester and State of New York, EARDLEY HARRY FORD, a subject of the King of Great Britain, and resident of Brooklyn, in the county of Kings, city and State of New York, and IRWIN ELLIOTT, a 10 citizen of the United States, and resident of the borough of Manhattan, city, county, and State of New York, have jointly invented certain new and useful Improvements in Pump-Operating Mechanism for 15 Wafer-Baking Machines, of which the following is a specification.

Our invention relates to mechanism for operating pumps, particularly in connection with machines in which the pump supplies 20 batter to suitable molds or plates for baking wafers and the like. The object of our invention is to provide a pump-operating mechanism which will be positive and reliable in its action, and which will not be affected injuriously by the heat of the wafer-baking machine or the like.

In order to give an illustrative instance of the application of our invention, we have shown it in connection with a wafer-baking 25 machine of the general type disclosed in Letters Patent of the United States No. 1,196,147 issued to W. E. Prescott on August 29, 1916. It will be understood, however, that our invention may be applied to 30 other machines as well, and that various modifications may be made without departing from the nature of our invention as defined in the appended claims.

In the accompanying drawings, Fig. 1 40 is a side elevation of a wafer-baking machine provided with our improved pump-operating mechanism; Fig. 2 is a vertical cross section taken substantially on line 2-2 of Fig. 1; Figs. 3 and 4 are detail 45 side elevations, on an enlarged scale, showing a portion of the pump-operating mechanism in two different positions; Fig. 5 is a vertical section on line 5-5 of Fig. 3; Fig. 6 is a partial plan view of the right-hand 50 end of Fig. 1, showing two of the molds and the pump used in connection with our machine; Figs. 7 and 8 are a transverse and a longitudinal section respectively through

the pump, Fig. 7 being taken on line 7-7 of Fig. 8, and Fig. 8 on line 8-8 of Fig. 55 7; and Fig. 9 is a vertical section taken on line 9-9 of Fig. 6.

The baking-machine illustrated comprises a suitable frame 20 supported on legs 21 and provided with upper track portions 22 and 60 lower track portions 23, connected by curved track portions 24, 25, all of these track portions together forming an endless track on which are adapted to travel rollers 26. These rollers are mounted on molds or plates 65 27, each mold being shown with two pairs of rollers and the adjacent portions of consecutive molds are connected, at the roller axes, by pivoted links 28 so as to form an endless chain of molds. To each of the 70 molds or plates 27 is pivoted about an axis 29 extending lengthwise of the path of travel, a cover 30, normally held against the respective mold by a locking member 31 which is secured to the outer end of a shaft 75 32 journaled in the mold and extending at right angles to its plane, that is to say vertically while the molds are in a horizontal position. At its inner end, each shaft 32 has a star-wheel 33 adapted to engage two 80 stationary operating pins or projections 34 and 35 located at suitable points of the machine, see Fig. 1. Each cover 30 is provided at the side opposite to the hinge 29, with an extension 36 carrying a roller 36' 85 adapted to travel along a curved guide 37 which is located at the track portion intervening between the operating projections 34 and 35. During the major part of the travel, the cover 30 is locked to the respective mold or plate 27, but when the star- 90

wheel 33 reaches the first projection, 34, the shaft 32 is given, automatically, a partial turn which brings the locking member 31 to the releasing position. The cover 30 is 95 then free to swing on the hinge axis 29, and by the action of the guide 37 on the roller 36' is caused to swing away from the mold or plate 27, thus enabling the cover (which now stands about vertical, at one side of the 100 conveyor or chain) to clear the batter-nozzle hereinafter referred to, and the mold to receive its supply or charge of batter. The guide 37 is so formed as to then bring the cover 30 back against the mold or plate 105 27, and immediately thereafter the star-

wheel 33 will engage the second projection, 35, thereby automatically turning the shaft 32 to restore the member 31 to the locking position. The molds, with the covers closed 5 upon them, travel through a baking chamber formed with a hood 38 and heated in any suitable manner (say by burners 39), and the baked wafers or other articles are removed or allowed to drop off as soon as the 10 cover has been swung open, it being understood that the travel of the molds is relatively slow. The mechanism so far described is substantially the same as in the Prescott patent referred to above.

15 At the track portion adjacent to which the guide 37 is located, on one side of the machine, we provide two stationary guides 40, 41 parallel to the upper track portion 22 and preferably above the same, and along 20 these guides is adapted to slide the casing 42 of a pump which may be of any suitable character. We have illustrated herein a pump corresponding in its general arrangement to the one described and shown in Letters Patent of the United States No. 852,694 issued to George Samuel Baker on May 7, 1907. In the present case, however, we have shown a single-discharge pump instead of the Duplex pump shown in the Baker patent.

25 The suction inlet 43 is suitably connected with a batter receptacle (not shown), and has a connection, controlled by a suction valve 44, with the main chamber 45 of the pump. From this chamber another connection, controlled by a delivery valve 46, leads to the discharge pipe 47 provided with a nozzle 48, said pipe and nozzle being rigid with the pump casing 42 and therefore moving in unison therewith. Within the chamber 45 the piston 49 is mounted to slide in a direction parallel to the guides 40, 41, that is to say, parallel to path of the pump casing 42. During the greater part of the movement of the pump casing, the piston 40 will move in unison therewith, but as the casing 42 nears either end of its stroke, a relative movement of casing and piston will be effected in the following manner: The piston 49 is provided with a rod 50 parallel 45 to the guides 40, 41 and projecting from the casing 42 at each end. The forward end of the piston rod 50 is adapted to engage a stationary abutment 51, toward the end of the forward movement of the pump casing 42, and toward the end of the return movement of said casing, the rear end of the piston rod is adapted to engage a stationary abutment 52. Preferably this abutment is adjustable lengthwise, for which 50 purpose it may be formed as a rod journaled and sliding in a stationary bearing 53 and screw-threaded in a normally stationary block 54, so that by turning the handle 55 the abutment rod 52 may be moved forward 55 or rearward in the block 54. In some cases

it may be desirable to throw the pump out of action temporarily; this may be accomplished by withdrawing the abutment 52 from the path of the piston rod 50. In the particular construction shown, the block 54 70 is a slide movable lengthwise in a casing or guide 56 to which the bearing 53 is attached, but under normal conditions the block 54 is held against longitudinal movement by a locking pin 57 engaging a suitable recess in 75 said block. The pin 57 is movable transversely, so as to enable it to be thrown out of engagement with the block 54, and may be mounted to slide in the casing or guide 80 56 as shown, being connected pivotally with a lever 58 mounted to swing about a stationary fulcrum 59 and provided with a handle 58'. A spring 60 tends to throw the lever 58 and pin 57 inward into the locking position. When the block 54 is released from the pin 57, a simple outward or rearward pull on the handle 55 will cause the block 54 to slide in unison with the abutment rod 52, thereby enabling the latter to be removed quickly from the path of the piston rod 50. 90

The following novel mechanism is provided for reciprocating the pump casing 42 along the guides 40, 41: At its side, the casing 42 has a pivotal connection 61 with a rod 62 of considerable length, said rod 95 extending forwardly first through a compartment 63 open to the outside air and separated from the main or heating chamber of the hood 38 by a partition 64. The rod 62 then passes through a slot 65 in the curved front wall 66 of said compartment and at its front end has a pivotal connection 67 with a crank arm 68 secured to a transverse shaft 69 journaled in a stationary bearing 70. The shaft 69 projects to the outside of the hood 38 and on its outer portion carries rigidly a toothed sector 71. The latter is in mesh with a toothed sector 72 mounted loosely on a shaft 73 and provided with a roller or other projection 74 fitted into a continuous cam groove 75 of a disk 76. This disk is journaled on a stationary stud 77 and is made with a pinion 78 meshing with a toothed wheel 79 rigidly secured to the shaft 73. 105

The shaft 73 may also carry projections 80 for causing the conveyor or chain of molds to be moved continuously in the direction indicated by the arrow. The drive may be of any suitable kind, for instance by means of a belt pulley 81 moving in unison with a pinion 82, in mesh with a gear wheel 83 on a shaft 84 also carrying a pinion 85 meshing with a toothed wheel 86 rigid on the shaft 73. 110

The operation of the machine, and particularly of the pump-operating mechanism, is as follows: Figs. 1 and 3 illustrate the position of parts at the beginning of the return stroke of the rod 62 and pump casing 120 125 130

42 (that is, at the beginning of their movement toward the right). The roller or projection 74 is about to enter the steep or quick return portion of the cam groove 75, which 5 will cause the sector 72 to turn quickly in the direction indicated by the arrow (counter-clockwise), producing a similarly quick movement of the sector 71, arm 68, rod 62, and pump casing 42. The latter moves to-
 10 ward the right, carrying with it the piston 49 and its rod 50 until the latter strikes the abutment 52, if it is in operative position. This engagement of the piston rod 50 with the abutment 52 occurs shortly before the
 15 parts reach the position shown in Fig. 4, which illustrates the end of the return stroke. As the rod 50 and piston 49 are held stationary by the abutment 52 while the pump casing 42 continues to move to-
 20 ward the right, the size of the main pump chamber 45 is increased, thus producing suction which will cause batter to be drawn into said chamber through the inlet 43 and past the valve 44. At the end of the return
 25 stroke, the parts have reached the position shown in Fig. 4, and then follows the forward stroke (to the left), either immediately, or after a short interval during which the pump casing remains stationary, if the
 30 cam groove 75 is made with a short portion concentric with the stud 77, as shown immediately above the projection 74 in Fig. 4. During this forward stroke, the piston 49 and rod 50 will move in unison with the pump casing 42 until the left-hand end of the rod 50 engages the abutment 51. From this moment on, the pump casing 42 will move alone toward the left, the piston 49 remaining stationary. The relative movement
 35 of pump casing and piston thus obtained will reduce the volume of the main chamber 45 and consequently expel the contents of said chamber through the delivery valve 46, discharge pipe 47, and nozzle 48 into the open
 40 mold or plate 27 which at that time is moving under said nozzle. It will be noted that the cam portion which effects the forward or delivery stroke of the pump casing 42 is
 45 comparatively shallow, that is to say, its circumferential or angular extent is considerably greater than that of the steep cam portion which effects the return or suction stroke of the pump casing 42. It is desirable that
 50 the delivery of the batter through the nozzle 48 should continue for a relatively long period, so that the batter may be thoroughly distributed throughout the length of the mold or plate 27. On the other hand, a
 55 quick action of the pump on the suction stroke will conduce to efficiency in filling the main chamber 45 with batter.

It will be noted (see particularly Fig. 8) that one face of the piston 49 forms a movable wall of the chamber 45, the other face

(at the left in Fig. 8) being exposed to the atmosphere. Preferably, on this side, an additional guide is provided for the piston rod 50, say by securing to the casing 42 a cross bar 42' through the central portion of which the piston rod is adapted to slide.

The toothed sectors 71 and 72 are in mesh at all times during the operation of the machine, thus insuring proper working of the parts. These sectors, as well as the projection 74 and cam 76 with its drive 78, 79, are located exteriorly of the baking chamber and exposed to the cooling influence of the outside air, so that these parts are not liable to be warped or otherwise affected injuriously by the heat applied to the baking chamber.

It will be understood that after a mold or plate 27 has received its supply of batter from the pump, the cover 30 of said mold or plate is closed automatically by the action of the guide 37, and the closed mold passes through the baking chamber. The baked wafers are removed, or allowed to drop out, when the guide 37 again swings the cover 30 into the open position.

By turning the handle 55, the abutment 52 may be adjusted lengthwise to vary the effective suction stroke of the pump, and therefore the amount of batter drawn in and delivered at each complete (to and fro) reciprocation of the pump casing 42. If it is desired to stop the supply of batter temporarily (as in testing the operation of the other parts of the machine), the abutment 52 may be removed entirely from the path of the piston rod 50, either by continued turning of the adjusting handle 55, or preferably (since this is quicker) by moving the pin 57 out of its locking position and then sliding the block 54 and abutment 52 outwardly (to the right).

We claim as our invention:

1. In a machine of the class described, a conveyor, a guide ranging lengthwise of said conveyor, a pump barrel movable along said guide and adapted to discharge material on articles carried by said conveyor, a piston arranged to travel within said barrel in the same direction in which the pump barrel moves and provided with a rod projecting at each end of the barrel, stationary abutments adapted to engage the ends of the piston rod and to cause a relative movement of the piston within the barrel as the latter continues to move after such engagement, a shaft in operative connection with the conveyor, a rocker operated by said shaft, and an operative connection between the rocker and the pump barrel, to cause the latter to reciprocate along said guide.
2. In a machine of the class described, a conveyor, a guide ranging lengthwise of said conveyor, pump mechanism movable along said guide and adapted to discharge

material on articles carried by said conveyor, a shaft in operative connection with said conveyor, a rocker operated by said shaft, another rocker in permanent driving connection with the first-named rocker, and an operative connection between the second rocker and the pump mechanism to cause the latter to reciprocate along said guide.

3. In a machine of the class described, a conveyor, a guide ranging lengthwise of said conveyor, pump mechanism movable along said guide and adapted to discharge material on articles carried by said conveyor, a shaft in operative connection with said conveyor, a rotary cam operated by said shaft, a toothed rocker operated by said cam, another toothed rocker permanently in mesh with the first-named rocker, and an operative connection between the second-named rocker and the pump mechanism to cause the latter to reciprocate along said guide.

4. In a machine of the class described, a conveyor, a guide ranging lengthwise of said conveyor, pump mechanism movable along said guide and adapted to discharge material on articles carried by said conveyor, a toothed rocker in permanent operative connection with the conveyor, and another toothed rocker, in permanent mesh with the first-named rocker and in permanent operative connection with said pump mechanism to cause the latter to reciprocate along said guide.

35 5. In a machine of the character described, a conveyor, a chamber through which said conveyor passes at a portion of its path, a guide ranging lengthwise of another portion of the conveyor's path, pump mechanism movable along said guide and adapted to discharge material on articles carried by said conveyor, rotary mechanism located exteriorly of said chamber and in permanent operative connection with the conveyor, a rocking device in permanent

operative connection with the said rotary mechanism and extending from the latter into said chamber, and a connecting rod extending from said rocking device lengthwise of the conveyor to said pump mechanism, to cause the latter to reciprocate along said guide.

6. In a machine of the character described, a conveyor, a guide ranging lengthwise of said conveyor, a pump movable along said guide and adapted to discharge material on the articles carried by the conveyor, said pump including a member movable relatively to other parts of the pump, abutments located in the path of said member to engage the same and produce suction and delivery, means whereby one of said abutments may be adjusted lengthwise of the path of the pump to vary the output of the pump, and means for releasing said abutment so that it may oppose no resistance to the said member and allow the pump to move without pumping action.

7. In a machine of the character described, a conveyor, a guide ranging lengthwise of the conveyor, a pump movable along said guide and adapted to discharge material on the articles carried by the conveyor, said pump including a member movable relatively to the other parts of the pump, abutments located in the path of said member to engage the same and produce suction and delivery, a normally stationary block carrying one of said abutments and slidable bodily with the abutment, when the block is released, in a direction parallel to the path of the pump, screw mechanism for adjusting said abutment relatively to said block, and means for locking the block normally against sliding movement.

In testimony whereof we have signed this specification.
